Specification for Design.

Patented June 10, 1919.

Application filed March 10, 1919. Serial No. 281,877. Term of patent 3½ years.

To all whom it may concern:

Be it known that I, GIUSEPPE MONTRONI, a subject of the King of Italy, residing at Hoboken, in the county of Hudson and State of New Jersey, have invented a new, original, and ornamental Design for Hand-Bag Frames, of which the following is a specification, reference being had to the accompanying drawing, forming part thereof.

The figure is a front elevational view of a hand-bag frame, showing my new design.

I claim:

The ornamental design for a hand-bag frame, as shown.

GIUSEPPE MONTRONI.
